HOOD FOR A RANGE

James H. Shelton, 2849 N. Bend Road, Cincinnati, Ohio

Filed May 19, 1964, Ser. No. 80,062

Term of patent 14 years

(Cl. D81—25)

FIG. 1

FIG. 2

FIG. 4

FIG. 3

FIG. 1 is a perspective view of a hood for a range, showing my new design;

FIG. 2 is a top plan view thereof;

FIG. 3 is a front elevational view thereof; and

FIG. 4 is a side elevational view thereof.

The side opposite that shown in FIGS. 1 and 4 is a mirror image thereof.

I claim:

The ornamental design for a "hood for a range," as shown and described.
